CLAIM

The ornamental design for a sectional boat, substantially as shown and described.

DESCRIPTION

FIG. 1 is a top perspective view of the sectional boat comprising the invention;

FIG. 2 is a plan view of the sectional boat;

FIG. 3 is an elevation view of the sectional boat;

FIG. 4 is a bottom perspective view of the sectional boat showing the sections slightly separated;

FIG. 5 is a bottom view of the sectional boat as it appears when nested together for transport or storage;

FIG. 6 is a top view of the sectional boat as it appears when nested together for transport or storage;

FIG. 7 is a rear or aft elevation view of the sectional boat;

FIG. 8 is a front or forward elevation view of the sectional boat.

FIG. 2

FIG. 3
